UNITED STATES PATENT OFFICE

169,639

JUVENILE TRACTOR

Viktor Schreckengost, Cleveland Heights, Ohio,
assignor to The Murray-Ohio Manufacturing Company, Cleveland, Ohio, a corporation of Ohio

Application April 16, 1952, Serial No. 19,344

Term of patent 14 years

(Cl. D34—15)

To all whom it may concern:

Be it known that I, Viktor Schreckengost, a citizen of the United States, residing at Cleveland Heights, county of Cuyahoga, and State of Ohio, having invented a new, original, and ornamental Design for a Juvenile Tractor, of which the following is a specification, reference being had to the accompanying drawings, forming a part thereof.

Fig. 1 is a view in perspective taken from a point at one side, and slightly above and to the front of the juvenile tractor showing my design;

Fig. 2 is a top view of the juvenile tractor;

Fig. 3 is a front elevational view of the juvenile tractor; and

Fig. 4 is a rear elevational view of the juvenile tractor.

I claim:

The ornamental design for a juvenile tractor, substantially as shown.

VIKTOR SCHRECKENGOST.
